UNITED STATES PATENT OFFICE

JAMES O. NASH, OF DUKE, OKLAHOMA

PUMP

Application filed August 5, 1927. Serial No. 210,890.

This invention relates to pumps of the type disclosed in Letters Patent, No. 1,639,956, granted to me August 23, 1927, the object of the present improvements being to increase 5 the capacity of the apparatus and to provide means whereby the pump may be manually operated without exposing the operator to possible injury through contact with the power driving elements. Another object of 10 the invention is to provide means for avoiding wear and binding around the fulcrums of the operating lever and also to provide a very simple and inexpensive means whereby delivery of the liquid raised by the pump at a high elevation 15 will be facilitated. The invention is illustrated in the accompanying drawing and will be hereinafter fully set forth.

In the drawing:

Figure 1 is an elevation of an apparatus 20 embodying the present invention;

Fig. 2 is an enlarged detail section on the line $\times-\times$ of Fig. 1, and

Fig. 3 is an enlarged sectional elevation of 25 the structure whereby wear upon the pivots is avoided.

In carrying out the present invention, I employ a substantial supporting frame consisting of posts 100 connected rigidly by braces 101 having tenoned connections with 30 the respective posts and provided in any desired number. If desired, diagonal braces may be provided between the braces 101. The posts and braces are so arranged as to provide guides for pump rods and the supporting 35 frame is erected around the mouth of a well so that the pump rods will be arranged to operate within barrel or pump casings depending into the well. In the drawing, I have shown four barrels 102, 103, 104 and 105, 40 and it will be noted that these pump barrels rise to different heights within the frame. At the upper end of each pump barrel, there is fitted thereto a sleeve 106 which is internally threaded and within the sleeve there are 45 provided disks 107 which have threaded connections with the sleeve. The opposed faces of these disks are preferably concave, as shown at 108, and between the disks packing 109 of any preferred or approved type is provided, the disks being provided with central

openings through which the pump rod 110 passes and the packing fitting about the pump rod and being compressed around the same by adjusting the disks in an obvious manner. Each disk is provided with an angular hub 55 or collar 111 on its plane face so that it may be easily engaged by a turning tool, and it will be understood that rotation of either disk will cause it to move longitudinally of the coupling sleeve and thereby compress the 60 packing. This structure is exceedingly cheap and may be applied to any pump barrel. The discharge spout 112 of the pump leads laterally from the pump barrel at a point below the upper end of the same and communicates 65 directly with a pipe 113 which may be carried to any point of delivery and it will be understood that the spout may be of any approved form and secured or coupled to the barrel in any convenient manner. Many 70 pumps leave the upper ends of the barrels entirely open and the water will be lifted to the discharge spout 112 but if the delivery pipe 113 extends to a level above the horizontal plane of the discharge spout, the water will 75 simply overflow through the upper end of the barrel. By providing the packing sleeve and the compressing disks shown in detail in Fig. 2, I close the upper end of the pump barrel and any air which may be in the barrel above 80 the level of the discharge spout will be compressed by the rising of the water in the barrel and will exert a pressure upon the water or other liquid which will coact with the force exerted by the pump rod and the plunger or 85 piston so that the water may be delivered wherever desired.

The innermost pump barrel 102 rises to a point near the top of the supporting frame and the pump rod 110 thereof is formed with or rigidly secured to a driving bar 114 which may extend up to a windmill so that the pumps may be operated by the power generated by the wind wheel. Pivoted to the sides of the driving bar 114 are pendent links 90 115 which have their lower ends pivotally engaged with metal straps 116 secured to the sides of a wooden bar 117 and projecting beyond the ends of said bar in order to accommodate the links and be pivotally connected 95 100

therewith. The wooden bar or body 117 and the straps 116 secured to the sides of the same constitute a lever or walking beam which will oscillate as the driving bar 114 is reciprocated. 5 The lever is fulcrumed between adjacent posts 100 upon a pin 118 which passes through the posts adjacent the inner edge thereof. In wet weather, the wooden bar 117 absorbs moisture and swells so that it tends to bind about the pivot pin and thereby cause the pump to operate with difficulty, besides causing excessive wear upon the contacting surfaces. To overcome this difficulty, I provide a bushing 119 which extends through the lever and fits 10 around the pivot pin or bolt so that the swelling of the wooden body will not cause binding upon the pivot. To prevent rotation of the bushing relative to the wooden lever body, a keyway is formed through the body and the bushing is provided with a longitudinal 15 radial rib 120 seating in the keyway, as shown in Fig. 3. I also provide an oil cup 121 which is carried by the lever and has its outlet extending through the lever to deliver lubricant 20 through an opening provided therefor in the bushing to reach the opposed surfaces of the bushing and the pivot. The bushings and oil cups will be generally provided also at the pivotal connections between the levers and 25 the links to be presently mentioned.

The driving rod 114 is guided by rollers, indicated at 122, and a similar driving rod is provided in alignment with each pump barrel, the several driving rods being designated 123, 124 and 125. To each of these 30 lower driving rods are pivoted links 126 corresponding in all respects to the links 115, and levers 127, 128 and 129 are pivotally connected to the respective links so as to 35 actuate the several driving rods 123, 124 and 125. These levers are pivotally mounted in the frame in the same manner as the upper lever, which has been described, is mounted, and it will be noted that the respective pivots 40 130, 131 and 132 are disposed in different vertical planes so that a line passing through all the pivots will be parallel with a line passing through the tops of the several pump barrels, the leverage exerted upon each driving 45 rod and connected pump rod, consequently, being the same. A diagonally disposed connecting rod or link 133 is pivoted at its upper end to the outer end of the topmost lever and at its lower end to the inner end 50 of the lever 127 coincident with the pivotal attachment of the links 126 thereto. A similar inclined link or connecting bar 134 is likewise connected to the levers 128 and 129 and the levers 127 and 128 are connected by a 55 link 135 which is pivoted to and extends between the outer ends of the same. The levers 127 and 128 will, consequently, always move in the same direction while the topmost lever will move in opposition to the 60 65 lever 127 and the lever 129 will move in

opposition to the lever 128, the movements of the several pump rods being thereby balanced. Interference between the several pump rods and the levers will not occur inasmuch as the metallic straps secured to the sides of the wooden bodies pass beyond the ends of the levers and when any pump rod moves toward a superposed or a subjacent lever, the end of the rod will pass through the space between the ends of the metallic 70 straps and beyond the end of the wood lever body. This feature is advantageous where, for any reason, the vertical distance between levers must be restricted. The lowermost lever 129 is provided with an opening 136 75 therethrough at its outer end so that it may be pivotally connected with a pump jack driven by a steam engine or other convenient motor, or may have a handle connected thereto. If preferred, a pump jack may be connected to one of the upper levers. This arrangement provides for an efficient operation of a plurality of pumps within a single well and will be particularly advantageous in irrigation projects inasmuch as the well may 80 be made of large diameter to accommodate a large number of pumps and the water raised by the several pumps may be delivered at different points so that the benefits thereof may be spread over a considerable territory. 85 The discharge from two or more pumps may be delivered at one point and many forms or arrangements of pipe connections may be employed between the outlets.

In some localities, it may be inconvenient 100 to obtain mechanical or electrical power for operating the pumps and manual labor may be obtained at a very low cost. To meet this condition, I provide a coupling bar 137 which is pivoted at its upper end to the 105 uppermost driving rod 114 and is offset therefrom, as shown at 138, so that it may be disposed at that side of the pumps opposite the side at which the several lever elements are applied. This coupling bar 137 depends to 110 a point near the ground and is pivoted to a lever 138' corresponding in construction to the levers 127, 128 and 129 and projecting outwardly from the side of the supporting frame upon which it is pivoted. To the outer end of this lever 138' is secured a handle 139 which may be manually grasped and operated, and it will be understood that a cross bar of any desired length may be fixed 115 to the handle so that a large number of laborers may be enabled to grip the same and operate the apparatus. If necessary, a handle and cross bar may be attached to the lever 129, and it will be understood that the frame and series of pumps may be duplicated to any extent permitted by any given 120 circumstances.

Having thus described the invention, I claim:

In a pumping apparatus of the type de- 125

scribed, a plurality of levers, a link pivoted to and connecting the outer ends of intermediate levers, a link pivoted to and connecting the inner end of the lowermost lever with the outer end of the next lever above, a link pivoted to the outer end of the uppermost lever and to the innermost end of the next subjacent lever, and means for applying power to one of the levers.

10 In testimony whereof I affix my signature.
JAMES O. NASH. [L.S.]
